UNITED STATES PATENT OFFICE.

ISAAC BERNSTEIN, OF NEW YORK, N. Y.

GARMENT HOLDER AND SHAPE RETAINER.

1,073,084.

Specification of Letters Patent. Patented Sept. 16, 1913.

Application filed December 7, 1912. Serial No. 735,396.

To all whom it may concern:

Be it known that I, ISAAC BERNSTEIN, a citizen of the United States of America, residing at New York city, borough of Manhattan, county and State of New York, have invented certain new and useful Improvements in Garment Holders and Shape Retainers, of which the following is a full, clear, and exact description.

10 This invention relates to devices for supporting garments particularly ladies' dresses.

While my improvement supports the garments placed thereupon, it acts more particularly to keep the garments in shape, especially when said garments are packed in a trunk, box or dress suit case. To adapt the garment-holder, or shape retainer for packing purposes, I form it out of a plurality of flat sections which are foldably connected by a hinge or analogous device.

25 My improved garment-holder is preferably made out of flat material, such as paper, celluloid, or even metal, and is preferably provided with supplemental hip members and also with bust members, which are designed to lie flat against the form when not in use.

With the aid of my improved garment-holder the shape of a dress can be maintained when said dress is packed away or when hung in a closet. By reason of the fact that the garment-holder is provided with bust-elements, a dress can be mounted thereupon for display purposes, a removable head portion being provided to enhance the appearance of the displayed dress.

30 I will now proceed to describe my invention in detail, the novel features of which I will point out in the appended claims, reference being had to the accompanying drawings, forming part hereof, wherein—

40 Figure 1 is a front view of my improved garment-holder; Fig. 2 is an edge view thereof; Fig. 3 is an edge view illustrating the holder as folded for packing purposes; and Fig. 4 is a diagrammatic face view illustrating a garment as hung upon the holder.

45 As illustrated in Fig. 1 my improved garment-holder consists of a flat structure comprising the skirt portion 1 and bust portion 2 connected together at 3 by hinges 4. The skirt portion 1 is provided with flat supplemental hip members 5 which are extensibly connected to the skirt portion 1 as at 6. As herein illustrated, the extensible con-

nection consists of slots 6^a, in the supplemental hip members 5, and rivets or eyelets 7 which are secured to the skirt portion 1. The rivets or eyelets 7 pass loosely through the slots 6^a, but the heads of the said rivets keep the supplemental members 5 flat against the skirt portion 1. The supplemental members 5 can be moved outwardly, as per dotted lines in Fig. 1 to increase the width across the hip region.

50 A further feature of my improvement consists of the bust members 8 comprising the flat strips 9 the ends of which are slidably secured to the bust portion 2 by rivets or eyelets 10. The strips 9 are preferably yieldable in order that they can be bowed upwardly into a bust-like configuration (see dotted lines Fig. 2) to cause the garment to stand out away from the flat holder to give a bust effect. For displaying purposes this feature of my invention is important, as a garment cannot be properly displayed unless a bust effect is produced.

55 When the strips 9 are bowed the rivets or eyelets 10 will slide in the slots 11 which are located in the flat bust portion 2. The rivets or eyelets 10 will be sufficiently upset to firmly but slidably secure the strips to the flat holder and whereby the strips will retain the curved or bust-like shape until flattened down by pressure.

60 To enhance the appearance of the structure while a garment is being displayed I provide a removable flat head section 12 which is preferably in the form of an envelop (see Fig. 2) and which will slip over the tongue or neckpiece 13 on the bust member 2 of the form.

65 When a garment is to be packed away it will be placed upon the holder as shown in Fig. 4. The holder and garment thereupon will be folded at the point 3 as shown in Fig. 3. When thus folded the garment will lie flat and free from wrinkles. A garment can be folded and placed in a trunk, suitcase or closet without fear of wrinkling when said garment is placed upon my improved holder.

70 The neck piece 13 is provided with an opening 14 through which a hook, or other suspending element can be passed for the purpose of hanging the garment in a closet or upon a rack.

75 A notch 15 is provided at the bottom edge of the skirt-portion, to aid in centering the holder when in the garment.

Having now described my invention, what I claim and desire to secure by Letters Patent is:

1. A garment-holder comprising a flat bust-portion, having a neck piece, and a flat removable head piece upon said neck piece, the head piece being in the form of an envelop adapted to slip over the neck piece.
2. A garment holder comprising a flat garment holding section, supplemental members slidably connected to said section, the outer edges of the members corresponding to the similar edges of the section and respectively registering at their upper ends, the outer edges of the members maintaining parallelism with the section edges throughout all possible movement of the members.
3. A garment holder comprising a flat

garment holding section, supplemental members slidably connected to said section, 20 the outer edges of the members corresponding to the similar edges of the section and respectively registering at their upper ends, the outer edges of the members maintaining parallelism with the section edges throughout 25 all possible movement of the members, the connection of the members to the section permitting the disposition of the members wholly within the edge outline of the section.

Signed at New York city, N. Y. this 5th day of December, 1912.

ISAAC BERNSTEIN.
